James J. Jackson.
Design for Name, corn, frame and summer piece.

Design No. 140

James L. Jackson, New York, N.Y.
Letters Patent No. 440 Dated Feb. 3, 1852

The Schedule referred to in these Letters Patent, and making part of the same

To all whom it may concern:

Be it known that I, James L. Jackson, of the City, County, and State of New York, have invented, or produced a certain new and original design for a mantle, Brate, Frame, and Summer-piece, and I do hereby declare the following to be a full, clear, and exact description of the same, reference being had to the accompanying drawings, making a part thereof, in which Figure 1. represents a front view, with such portion of the ornaments as are duplicates of those shown, omitted, and where the symmetry of the ornament would be marred by dividing it, they are shown in full. Figure 2. is an end view, showing the ornament on the pilaster, and sides of the bracket. Figure 3. is a vertical section through the whole (omitting the marble slab), which shows the projection of the several parts herein enumerated.

To enable others more fully to understand the nature of my design, I shall proceed to describe the same, with reference to said drawings, which will more clearly exhibit it, than can be done by description.

The extreme outside piece A. of the mantle is a plain slab, with a projection B. on it from which projects a rounded pilaster C. resting on a base D. which is ornamented with a plain moulding. The pilaster has a cap formed of several volutes D' with a small leaf between them, and from said volutes, is suspended a stem, bearing at intervals four bunches of flowers, in high relief, interspersed with leaves, which ornament the face of the pilaster. Inside of this is a plain moulding E. running entirely around the mantle, and forming two sides.

of a sunken panel F. in the upper corners, in which are placed a rich bouquet of flowers and fruit; the stems fastened by a ribbon, and having as a prominent flower in the right, a full blown rose G. with a bud and leaves of the same, and in the left a bunch of grapes pendant, with leaves of the vine. Three of the stems or vines of the bouquet, curve towards the three corners of the panel - the one I bearing leaves, and two full blown flowers, the others J. bearing foliage, full blown flowers, and buds, each of a different kind. The inner or curved side of the panel is flanked by a plain moulding similar to the outer sides, and from this moulding curves inwardly a curved or 'S' shaped moulding (seen at H fig 3) so as to leave a low plain surface I. as a back ground for the grate frame. In the centre of the mantle is a bracket M. which serves as a support to the slab N. and which is finished at the top by leaves O. having their points turned down, and which are underlaid by a plain heading P. below which is foliage, from which is suspended a group of flowers Q. The bottom of the bracket is finished by and terminates in foliage R. which rests against the plain surface I. The sides of the bracket are ornamented with a volute S. slightly projecting, and the ground laid with foliage T. which starts from a stem U. all of which is distinctly seen in fig 2. said figure also representing the outline of the bracket.

The grate frame, has on its outer edge two plain delicate mouldings a. which margin a cavetto moulding b. between them, ornamented with sunken ogee work c. and from the inner moulding starts a wide and deep cavetto d. (fig. 3) from the outer edge of which projects, so as to stand entirely clear of it, highly wrought arched foliage and stems e. The inner margin of the frame is finished with a moulding similar to its outer margin.

The summer piece is so made as to be removable at pleasure, having a plain outer margin, inside of which is a sharp

gothic head f, surrounding ornamental ^{open} work made up of circles g, with their radii h, and separated by small ring, the ground being open work. A deep concave moulding i, follows throwing back the inner part j, of the summer piece, which is highly wrought with arabesque figures, and foliage with open ground work. The extreme inner part of the summer piece is a panel with a semi-circular top, and filled up with arabesque figures and foliage, the top of which is a projecting shield k, with a lozenge l, in the centre, and arms m, radiating therefrom, branched at their outer ends, and terminating in pendants n, the ground-work being open.

The lower end of the summer piece is finished with a series of Gothic arches o, having the spaces between them in open work.

Having thus fully described the nature of my design, what I claim therein as new, and desire to secure by Letters Patent, is the combination and arrangement of the figures, flowers, and ornaments herein represented, the whole forming an ornamental design for a Mantle Grate frame and Summer piece.
